UNITED STATES PATENT OFFICE

112,346

DESIGN FOR A TIRE

Harry S. Mooradian, Dayton, Ohio, assignor to
The Dayton Rubber Mfg. Company, Dayton,
Ohio, a corporation of Ohio

Application July 19, 1937, Serial No. 70,518

Term of patent 14 years

To all whom it may concern:

Be it known that I, Harry S. Mooradian, a citizen of the United States of America, residing at Dayton, in the county of Montgomery and State of Ohio, have invented a new, original, and ornamental Design for a Tire, of which the following is a specification, reference being had to the accompanying drawing, forming a part thereof.

In the drawing:

Figure 1 is a plan view of a section of a tire showing my new design;

Figure 2 is a sectional view taken on the line 2—2 of Figure 1.

The design is characterized by circumferential ribs having fluted substantially horizontal surfaces, and transverse slots extending only partially across said ribs, but continuing in the same plane partially across the next adjacent rib, said slots being alternately arranged on opposite sides of each rib in a longitudinal direction thereof as shown in Fig. 1.

I claim:

The ornamental design for a tire, substantially as shown and described.

HARRY S. MOORADIAN.
